LUMINOUS SIGN

William W. Lillard, Ridgewood, N. J.

Application May 29, 1930. Serial No. 457,379

7 Claims. (Cl. 40—130)

The present invention relates generally to luminous signs and more particularly to signs whose characters and symbols are formed by light rays.

Large luminous signs designed to function at night, especially those used for advertising purposes, have usually been made by mounting a plurality of incandescent electric lamps on a frame or board, the lamps being positioned to outline letters and other characters in the words and symbols of the sign. Extra large luminous signs of this type have some objectionable features. A great many electric lamps are required. They consume a large amount of electricity. A strong and expensive frame is required to support the sign, especially if exposed to winds. The sign and the supporting frame are often unsightly when seen in daylight.

An object of the present invention is to provide less expensive means for producing very large luminous characters which are suitable for use as elements of signs.

Another object is to provide electric means for producing a large luminous sign which uses a relatively small amount of electric current.

Still another object is to provide devices for producing a large luminous sign for operation at night which devices will detract but little from the appearance of the surrounding country during the day.

In carrying out my invention, I mount lamps associated in a usual way with reflectors so as to direct rays or beams of light in desired directions for forming elements of characters. To cooperate with each lamp and its associated reflector, I mount an opaque member for arresting the ray of light at a point determined by the character of which the ray is to form a part.

A feature of my invention resides in the provision of means for intermittently arresting each light ray of a sign before it leaves its reflector, and for releasing the arrested rays suddenly so as to make the sign appear almost instantaneously out of the dark.

Other features and advantages will appear hereinafter.

In the accompanying drawing which forms a part of the specification:

Figure 1 is a diagrammatic view illustrating the appearance at night of characters formed by controlled light rays according to my invention.

Figure 2 is an elevational daylight view of a structure arranged for producing at night controlled light ray characters of an advertising sign.

Figure 3 is a diagrammatic elevational view partly broken away of an electric lamp, a reflector therefor, a shutter member for arresting the light rays of said lamp before they leave the reflector, and electric means for opening said shutter member quickly.

Figures 4 and 5 are side and bottom views re-

spectively of a form of light arrester which may be used in practicing my invention.

Figures 6 and 7 are front and side diagrammatic views, respectively, of equipment which may be mounted on the side of a hill for producing an advertising sign according to my invention.

Figure 8 is a diagrammatic side view of an arrangement of light reflectors and arresters illustrating how two controlled rays of light not in the same plane may be made to appear from a distance nearly like a single ray of light.

Figure 9 is a diagrammatic view illustrating the appearance at night, from the front, of the controlled rays of light produced by the devices shown in Figure 8.

Figure 10 is a diagrammatic view of an electric lamp and reflector unit such as may be used in practicing my invention, the lamp being shown connected to a source of electricity. A switch device is indicated for interrupting the electric current flowing through the lamp.

Figure 11 is a diagrammatic side view of equipment for producing a light ray sign, which equipment is mounted on a boat.

Figure 12 illustrates controlled light rays in colors.

Figures 13 and 14 are top plan and end diagrammatic views, respectively, of equipment for practicing my invention to produce the name of a town in large letters for aviators to read from above at night.

In practicing my invention, controlled rays of light are combined, usually at night, to form letters, figures and other characters and symbols. It will be seen as the description proceeds that the rays of light may be produced by such instrumentalities as electric incandescent lamps, electric carbon arc lights, or by devices burning materials such as gas or oil. In many cases electric incandescent lamps, generally designated as 10, (see Figure 3) can be advantageously used to provide the light rays to be controlled.

In controlling light rays of a lamp 10 according to my invention, the rays are first reflected in a desired direction by a fixed reflector 11 which in most cases can advantageously be parabolic reflectors of a well known type. A detailed description of the construction of the lamps 10 and reflectors 11 are not considered necessary for an understanding of the present invention.

It will be understood that the width, length and brilliance of the light rays desired for forming the light-ray characters in each case will usually determine the size and wattage of the electric lamps 10 and the proportionate size and shape of the accompanying reflectors 11.

In the drawing, is shown certain daylight views of equipment for producing light ray signs, and dot-and-dash lines in those views indicate the dimension and direction of a light ray that is to be produced and controlled at night.

In many cases, it will be advantageous to mount a suitable glass lens 12 on the reflector 11 of a lamp 10 for cooperation in a well known way with the reflector in concentrating and directing the rays of the lamp.

5 Control of the light rays of the lamp 10 for forming letters, etc. requires in addition to reflecting the rays in a certain direction, arresting the rays at a certain point which I do by interposing in the path of the rays an opaque member 13 made of metal or other suitable material and hereinafter called an "arrester".

10 An arrester may take the form of a truncated cone shaped vessel as illustrated in Figure 4 and have an end portion 14 and a shallow flared wall 15. It will be seen as the description proceeds that other widely varying forms of arresters may be used without departing from the broad scope of my invention.

15 20 An arrester 13 will preferably be positioned in the path of the reflected rays of a lamp 10 with the inside of the arrester turned toward the lamp, and with the end 14 intersecting all the rays of the lamp at substantially right angles. The entire inside surface of each arrester 12 will preferably receive a coating 16 of black paint or other suitable dark material that is a poor reflector of light rays. The outside surface of an arrester, in some cases, will receive a coating of paint 25 which will make the arrester less noticeable in daylight and which will also serve to help make the arrester invisible at night.

30 Where two light rays are directed at the same point and intersect each other as illustrated in Figure 2, an angular arrester 17 may serve for arresting both rays. The arrester 17 may be constructed similar to the arrester 13, and in some cases an arrester 17 may be made by bending a large arrester 13 along a diametrical through its end 14 so that one half of it is disposed at a substantial right angle to the other half. It will be understood that ordinary arresters for use with one lamp or angular arresters for use with two or more lamps may be made in other forms than curved. For example, certain two-way arresters shown in Figure 6 and designated as 18 have rectangular end portions.

35 50 In practicing my invention, a lamp and reflector unit including a lamp 10 and a reflector 11, may be mounted in any suitable way for cooperation with an arrester to produce a controlled light ray. Likewise arresters 13, 17 and 18 may be mounted in any suitable way for cooperation with the lamp and reflector units.

55 60 In Figure 2 is shown a structure illustrating how lamps 10, reflectors 11 and arrestors 13 and 17 may be mounted for producing a light ray advertising sign. It will be understood by those skilled in the art that the lamps 10 may be mounted in and supported by the reflectors 11 in well known ways. Two tall posts or columns 20 may be constructed of concrete or other suitable materials and a steel I-beam 21 may extend between the columns 20 and rest on their tops and be fastened thereto by any suitable means (not shown).

65 70 Certain down-turned reflectors 11 may each be fastened rigidly to one end of an arm 22 whose other end may be fastened rigidly to the I-beam 21 by angle pieces 23, or by any other suitable means. Other horizontally-directed reflectors 11 may be fastened to posts 24 set in the ground,

and in some cases two reflectors may be fastened to one post.

75 For producing the signs indicated in Figure 2, the arresters 13 and 17 may be fastened to posts 24 set in the ground. It can be readily seen that arresters 13 and 17 can be easily fastened to the I-beam 21 by means well known to mechanics should such an arrangement be desired for arresting light rays from upturned reflectors 11 mounted near the ground.

80 85 The effectiveness of a light ray advertising sign constructed according to my invention can often be increased by intermittently arresting and freeing part or all of the light rays forming the characters of the advertising sign. According to one way of arresting the rays of a lamp 10, the lamp and its reflector 11 may be enclosed in a box-like case 30 having one open end which may be closed by a pivoted shutter 31 (see Figure 3).

90 95 Remote control means for opening the shutter very quickly may include an arm 32 fastened to the shutter and a tensile spring 33 having one end fastened to the arm and the other to a supporting frame (not shown) for the reflector 11. The shutter 31 may be held closed by a pivoted latch 35 which may be released by energizing an electro-magnet 36 which will attract an armature 37 fastened to the latch 35 on the opposite side of a pivot 38 from a depending tooth 40 which holds the shutter 31 closed until the latch is released.

100 105 After the shutter 31 has remained open for a desired period of time it may be closed by manually operable means or by remote control means (not shown). It will be understood by those skilled in the art that other types of remote control shutter devices may be used in practicing my invention instead of the device shown in Figure 3.

110 115 According to another way of arresting a controlled ray of light in practicing my invention (see Figure 10), a lamp 10 mounted in a reflector 11 and connected by electric conductors 40 to a generator 41 may have a switch 42 mounted in the electric circuit leading from the generator 41 to the lamp 10. By opening the switch 42 the light ray of the lamp is arrested at its source without using any shutter.

120 125 Figures 6 and 7 illustrate how the side of a steep hill 50 may be utilized for inexpensively mounting lamp and reflector units and cooperating reflectors for producing a large light ray advertising sign. By mounting the lamp and reflector units and the arresters on posts 51 set in the side of the hill as is indicated in Figure 7 an expense for a tall structure such as is shown in Figure 2 is eliminated.

130 135 In will be noted from inspection of Figure 7 that the two light rays which will form the numeral 7 of the advertising sign will not be in the same plane. However, on viewing the sign at a considerable distance from the front of the hill at night the light rays forming the numeral 7 will appear to be substantially in the same plane, and also as being vertical. This feature of my invention is advantageous because of permitting a rough hill side to be utilized without building expensive structures for mounting the equipment necessary for producing a large light ray sign.

140 145 In Figures 8 and 9 is illustrated how two light rays controlled according to my invention may be arranged to cooperate and to form what will appear at a distance as substantially one light ray, the height of which is nearly equal to the sum of the height of the two separate rays. If desired, the reflector 11U and the accompanying lamp can

be made so small relative to the breadth of the ray from the lower reflector 11L that it will scarcely be noticed. The kind of built-up light ray shown in Figure 9 may be advantageously employed in 5 producing very tall light ray signs in mountainous countries.

Light ray signs embodying my invention may be mounted on movable objects which will often increase their effectiveness. In Figure 11, equipment is illustrated for producing a light ray sign which equipment is mounted on a boat 60. A structure including two tall masts 61 having a cable 62 stretched taut between them may serve the same purpose as the columns 20 and I-beam 21 shown in Figure 2. It will be understood that power for light ray signs carried on boats may be supplied by a generator (not shown) on each boat.

The appearance and effectiveness of a light ray sign embodying my invention may often be improved by providing well known means which will produce rays of colored light for use in the signs instead of white light. As can be readily seen by those skilled in the art each separate letter of a light ray advertising sign can often be produced in a different color. Various characters and symbols which may accompany an advertising sign may be shown in more than one color, as is illustrated in Figure 12. Also where only rays of white light are employed, the rays forming one letter of a 30 word may be made to appear stronger than the rays forming the other letters as is indicated in Figure 1, wherein the letter I is indicated as being brighter than the letter T.

In Figures 13 and 14, is illustrated how the name of a city, for example, "Avon" may be produced in very large letters by light rays employed according to my invention for the benefit of aviators flying at night. In this use of my invention, the equipment, such as the reflectors 11 and arresters 13 and 17 for controlling the light rays, may be mounted on posts 65 set in the earth and suitably located near an aviation landing field, if desired. It can be seen that the equipment for producing the name of a city can be placed on agricultural lands, for example, so as to occupy but little space needed for growing crops. In certain localities, light ray advertising signs can be constructed as illustrated in Figures 13 and 14 to be seen by people passing on 50 nearby roads at a considerable higher elevation than the signs.

Light ray signs will usually be relatively tall, varying from fifty to several hundred feet in height. Such being the case, a light ray sign will usually be positioned a considerable distance—in some cases a mile or more—from the place (road for example) where people will ordinarily be when looking at it. Thus the structure that may be required for mounting lamp and reflector units and arresters will scarcely be noticeable in the daylight. Furthermore, the structure for a light ray sign can often be painted a color effective to make the structure blend into the background.

Variations may be resorted to within the scope 65 of the invention, and portions of the improvement may be used without others.

Having thus described my invention, I claim:

1. In a sign, in combination, means for producing light, means for reflecting a beam of said light along a desired path, and means for arresting said reflected beam of light at a desired point and cooperating with said light means for producing a well defined beam of light throughout

its length, said arresting means including an opaque member positioned at said point to intercept said beam and having a rim portion extending a short distance from said member toward said light-producing means.

2. In a luminous sign, in combination, a lamp and reflector unit arranged for producing and reflecting a ray of light at a desired point, a second lamp and reflector unit arranged for reflecting a ray of light at said point, and a member effective for arresting both of said rays, said units positioned relative to each other so that said rays of light cooperate to form a character element of said sign, said arresting member having means to prevent glare and spreading of said rays, said means including a wall-like element around the area on said member engaged by said rays.

3. In a luminous sign, means for arresting a beam of reflected light disposed in an approximately upright plane, said means including a thin opaque member disposed in a plane approximately at right angles to said beam and rim elements extending from said member a short distance toward the source of said beam, said member and said rim elements being colored on their inside surfaces for absorbing light and being colored on their outside surfaces for blending into the background adjacent said sign, whereby said arresting means is inconspicuous in daylight.

4. A sign for use at night having characters made up of light rays, said sign including means for producing beams of light sharply defined throughout, and devices for controlling said beams whereby to bring them suddenly into view, said means including an electric lamp and a parabolic reflector therefor, said controlling devices including a housing for said reflector having a hinged door in front of the open end of said reflector and means for opening said door instantly.

5. A luminous character formed of two or more overlapping, aligned beams of light, each of said beams formed by cooperation of a lamp and reflector unit for producing the light beam and a bowl-like interceptor member for arresting the beam, the lamp and reflector unit of the second beam being disposed adjacent the interceptor member of the second beam between said last named interceptor and its associated lamp and reflector unit.

6. A luminous sign including, in combination, a boat having masts spaced apart thereon, a member extending between the upper portions of said masts, lamp and reflector units mounted on said member and on the hull of said boat, and bowl-like interceptors carried by said boat and said member and cooperating with said units for producing sharply defined beams of light, said units and said interceptors being disposed whereby said beams form characters of said sign.

7. A sign for directing aviators flying high at night to an airplane landing field, said sign including, in combination, means for producing a plurality of beams of light, devices for intercepting said beams of light, means for preventing glare adjacent said intercepting devices, and means for supporting said beam-producing means, said light-intercepting devices and said glare-preventing means in position to render said beams visible to aviators above said landing field, said light beams being arranged to form elements of characters in said sign.
